UNITED STATES PATENT OFFICE.

FRED D. KAHN, OF NEW YORK, N. Y., ASSIGNOR TO L. WOLF & CO., OF NEW YORK, N. Y.

DESIGN FOR A HAND-BAG, PURSE, OR SIMILAR ARTICLE.

No. 38,482.

Specification for Design.

Patented March 19, 1907.

Application filed February 11, 1907. Serial No. 356,936. Term of patent 7 years.

To all whom it may concern:

Be it known that I, FRED D. KAHN, a citizen of the United States, and a resident of the city of New York, borough of the Bronx, in the county and State of New York, have invented a new, original, and ornamental Design for a Hand-Bag, Purse, or Similar Article, reference being had to the accompanying drawing, in which the figure is a side elevation of a hand-bag, purse, or similar article, showing the design.

I claim—

The ornamental design for a hand-bag, purse or similar article herein shown.

FRED D. KAHN.
